ELECTRICAL ANALOGUE

Alexander Wolf and Burton D. Lee, Houston,
Tex., assignors to The Texas Company, New
York, N. Y., a corporation of Delaware

Application December 15, 1947, Serial No. 791,796

16 Claims. (Cl. 346—33)

1

This invention is concerned with the analysis of mechanical and electrical systems which obey Laplace's equation. It finds a variety of applications, including production control from underground fluid reservoirs, such as oil and gas fields.

This application is a continuation in part of our co-pending application Serial No. 674,904, filed June 6, 1946, now abandoned.

Ohm's law for the flow of electricity is expressed by the equation

$$I = -\frac{1}{p} \frac{\delta E}{\delta x} \quad (1)$$

where I is the current flowing through the unit of area of a section whose specific resistivity is p , and across which there is a voltage gradient

$$\frac{\delta E}{\delta x}$$

(x is normal to the area).

Darcy's law for the flow of fluids through porous media is

$$V = -\frac{k}{\mu} \frac{\delta p}{\delta x} \quad (2)$$

where V is the rate of flow of a fluid whose viscosity is μ through a unit area of a section having a permeability k , and across which there is a pressure gradient

$$\frac{\delta p}{\delta x}$$

(x is normal to the area).

The two laws are identical when

$$\frac{1}{p}$$

the reciprocal of specific resistivity, is made numerically equal to the ratio of permeability to viscosity, in which case fluid flow becomes directly comparable to current flow and electrical potential becomes directly comparable to pressure.

Electricity, if it be likened to a moving fluid, is incompressible. Consequently Ohm's law (Equation 1) may be combined with the equation of continuity for an uncomressed or incompressible fluid (i. e. one which does not suffer change in volume). The equation can be expressed as follows, for the flow of electricity

$$\frac{\delta I}{\delta x} \text{ and } \frac{\delta I}{\delta y} \text{ and } \frac{\delta I}{\delta z} = 0 \quad (3)$$

where x , y and z are the coordinates of a three dimensional space taken at right angles to each other.

2

If Equations 1 and 3 are combined, the result is Laplace's equation, viz.

$$\frac{\delta^2 E}{\delta x^2} \text{ and } \frac{\delta^2 E}{\delta y^2} \text{ and } \frac{\delta^2 E}{\delta z^2} = 0 \quad (4)$$

This equation governs the flow of electricity in a homogeneous isotropic conducting medium, but in view of the analogy between the flow of fluid (which does not suffer change in volume) in a porous media and the flow of electricity in the conductor, it may be taken as governing such fluid flows as well, i. e. the flow of electricity is analogous to the flow of fluids if the fluid is considered either as incompressible or uncomressed.

There are a number of engineering problems involving the investigation of steady-state dynamic systems in which force distribution can be expressed in terms of electrical potentials and in which Laplace's equation, as a practical approximation, may be considered as controlling. It has been proposed heretofore, to solve some of these problems (particularly that involving fluid flow in a porous medium) by constructing an electrical analogue. Such an analogue may take the form of a conductive model, say a pool of electrolyte, the shape of which is analogous to the system to be investigated, exterior forces operating upon the system being represented in the analogue by electrical potentials imposed across the model. The conductor of the model may be of the electronic type, i. e. a conductive solid. Electrons are introduced at one or more points in the model and displace free electrons throughout the conductor, so that electrons are forced to move out at another point, with resultant current flow. The conductor may also be of the ionic type, say a pool of electrolyte or an electrolyte dispersed in a body of gel, current flow being dependent upon the mobility of ions through the conductor, but with current flow and potential drop established in the conductor just as in the electronic conductors.

In both types of conductors, potentials and potential gradients may be determined by means of probes in contact with the points in question and connected to a potential measuring device such as a galvanometer. However, the collection of data by such means heretofore has been tedious and time consuming, with the result that electrical analogues for solution of problems of the type described have not been employed to the fullest extent.

The exploitation of an oil or gas field may be accomplished either by the expansion of the gas and oil in the producing formation, by displace-

ment of the gas and oil by another fluid, or by simultaneous expansion and displacement. Whenever the displacement of the oil or gas is the controlling factor there arises the problem of mapping the progress of the boundary between the fluid in place and the displacing fluid. This problem is of particular interest in the operation of a cycling project in a gas-condensate field. In such an operation "wet" gas may be produced from one or more wells which are commonly called extraction or output wells. The wet gas is sent to a processing plant where liquid condensate is removed. The "dry" gas remaining after removal of the liquid condensate is injected back into the producing formation through one or more wells, called injection or input wells, both to conserve the gas for future use and also to maintain the pressure in the field. In such a cycling operation it is essential to anticipate the manner in which the dry gas will spread through the field, because the ultimate recovery of wet gas, and therefore of valuable liquid products, depends largely on keeping the dry gas from breaking into the extraction wells until substantially complete production of wet gas has been achieved. It is thus necessary to know the shape of the boundary or fluid interface between the wet and the dry gas around the injection wells for various arrangements of wells and for various injection and extraction rates, so that a scheme can be selected which will postpone this break-through to the latest possible date while maintaining a given rate of extraction and thereby permit the maximum recovery of wet gas. After break-through of dry gas into an extraction well has occurred, it then may be necessary to determine the expected proportion of dry gas which will be mixed with the wet gas produced by the well.

Exploitation problems of the type described above and the application of electrical analogues to the solution thereof are discussed by Muskat in his book "The Flow of Homogeneous Fluids Through Porous Media." Unfortunately the mathematical solution of the type of problem outlined above can be carried out only for certain idealized arrangements of injection and extraction wells and then only for the simplest of boundary conditions. The mathematical solution for the well arrangements and boundaries which are encountered in actual practice is entirely impractical because of the excessive labor involved. The only feasible approach to the solution of these problems is through the use of models on a reduced scale. These models need not actually employ a porous medium and a fluid. As pointed out above, there exists, with certain assumptions, an exact analogy between the flow of fluid in a porous medium and the flow of electrical current in a conducting body of similar geometry.

If electrical currents proportional to the rates of injection and extraction of fluid are passed through such a conductor by means of electrodes located at points corresponding to the positions of the wells in the field, then the electrical potential distribution in the conductor is exactly analogous to the fluid pressure distribution in the field, and the current flow lines correspond to the fluid flow lines in the field. The study of fluid flow in an oil field is thus reduced to a study of current flow in an electrical conductor of suitable shape.

In making studies on electrical models employing electrolytic solutions the mapping of the fluid interface may be carried out by either of two

different known methods. The first of these methods, which has been applied quite widely, is by means of the ionic conduction or so-called electrolytic model. The electrolytic model consists essentially of an aqueous solution of an electrolyte held in a suitable porous medium to prevent excessive velocities on the part of the ions due to normal diffusion. The electrolyte may be any ionizable salt. The porous medium may be ordinary blotting paper or cardboard, or may be a hydrophilic gel made from gelatin, agaragar, or similar colloidal substances.

A color tracer is added to the electrolytic system to permit visual observation of the progress of the ions between the points of different electrical potential in the system. The color tracer may be a hydrogen ion indicator, such as phenolphthalein, contained in the electrolyte solution, in which case the negative electrodes represent the fluid source or injection wells in the corresponding flow system and the positive electrodes represent the extraction wells. The advance of negative ions as revealed by a color change of the indicator corresponds to the advancing fluid interface in the producing formation. In place of an indicator a colored ion may be injected into the system at the electrode corresponding to the injection well. In such a case a colorless solution of zinc-ammonium chloride may be employed as the electrolyte in the porous medium and a solution of copper-ammonium chloride may be injected at the positive electrodes. The progress of the blue copper-ammonium ions from the positive to the negative electrodes corresponds to the advancing fluid interface in the formation. The progress of the equivalent fluid interface may be observed and recorded by making photographs of the position of the colored areas of the model at various time intervals after the experiments are begun.

The electrolytic model gives the desired results quite rapidly but with inferior accuracy due to a loss of sharpness of the boundaries of the fluid interface as the pattern spreads out. It has been shown that the total effect of the several inherent errors of the electrolytic method may result in an overall error of as much as 25% in the determination of the volume of the formation flooded by individual injection wells. In view of this the results obtained with the electrolytic model are generally considered to be of a qualitative nature or at best only semi-quantitative.

A second method for carrying out such studies is by means of the electrical conduction or so-called potentiometric model. This model consists ordinarily of a pool of a conducting liquid, such as a dilute solution of copper sulphate in water. The bottom of the conducting pool is shaped such that the depth of the conducting liquid at any point corresponds to the actual quantity of oil or gas contained in the producing sand at the corresponding point in the formation. The periphery of the conducting pool is shaped to correspond to the geometrical boundaries of the formation. The necessary information for the construction of the conducting pool is obtained from an isopachous map of the formation on which the contour lines of equal sand thickness have been converted to represent actual oil content by correcting for sand volume and connate water content. For practical reasons the reduction in scale is much larger in the horizontal than in the vertical direction.

At points corresponding to the location of the various wells in the field vertical metallic elec-

5

trodes are introduced into the pool, usually through the bottom so as not to interfere with the measurements. Through these electrodes electric currents are passed into and out of the pool, the flow of current being either into or out of the pool depending upon whether the well represented is an injection or extraction well, and the magnitude of the currents being proportional to the fluid injection and extraction rates which are employed or which it is proposed to employ in the exploitation of the field. As already mentioned, the direction of current flow at any point in the conducting pool is then identical to the direction of fluid flow at the corresponding point in the oil-bearing formation, and the potential gradient at any point in the conducting pool is proportional to the pressure gradient at the corresponding point in the formation. Any element of fluid in the formation follows a path corresponding to a current flow line in the conducting pool and the transit time for such element of fluid from one point to another in the formation is proportional to the line integral

$$\int \frac{\partial x}{\partial P} dx$$

taken along a flow line in the formation, where x is the travel distance and P is the pressure. Hence the transit time for any element of fluid in the formation is also proportional to the line integral

$$\int \frac{\partial x}{\partial V} dx$$

taken along a current line in the conducting pool, where x is the corresponding travel distance in the pool and V is the potential.

The problem of mapping the progress of an interface between the driving and the driven fluids is essentially the problem of determining these integrals along all of the current lines in the electrically conducting pool. The potentiometric method, however, has not been employed extensively, because heretofore the means for obtaining the line integrals have been too cumbersome for practical application. The method which has been employed previously for arriving at fluid travel time by means of potentiometric model studies is tedious and time consuming.

Co-pending application Serial No. 791,797, filed December 12, 1947, by Alexander Wolf discloses and claims an apparatus which greatly facilitates the collection and utilization of data with electrical analogues of steady-state systems that are governed, at least approximately, by Laplace's equation. The Wolf apparatus comprises a three dimensional electrically conductive model analogous to the system to be investigated, a chart (say one corresponding to a plan of the model), means for establishing across the model a current analogous to force operating upon the system, a conductive probe disposed in contact with the model, means for determining the potential of the probe, a marker disposed adjacent the chart, and a linkage connecting the marker to the probe for moving the marker on the chart to correspond to movements of the probe on the model.

In accordance with the instant invention at least two contacts are provided on the probe, with corresponding multiple tracing points on the marker, the linkage being such that the tracing points move on the chart to correspond to the movements of the contacts on the model. Thus, for example, if it is desired to plot lines of equipotential in the model, the probe may be equipped

6

with a rotatable head upon which a pair of contacts are fastened in spaced relationship. Similarly the marker member is provided with a rotatable head, provided with a pair of tracing points spaced to correspond to the contacts, the axes of rotation of the two heads bearing similar relationships respectively to the model and the chart. The mechanical linkage is such that the two heads move in unison and correspondingly respectively over model and chart and rotate correspondingly so that when the contacts are on an equipotential line in the model, with no potential difference indicated by a galvanometer connected across them, a corresponding line will be indicated by the tracing points on the chart.

The use of two or more contacts, with the plurality of markers permits equipotential lines to be plotted much more rapidly than when only single contacts or probes with single markers are employed. Moreover, if one set of markers is disposed at right angles to a set of probes or contacts but arranged to rotate in unison therewith, flow lines may be plotted directly, with additional savings in time.

We prefer to employ a rotatable probe head having multiple contacts thereon, with a corresponding rotatable marker head with multiple markers. The marker head is linked to the probe head mechanically so that the two move respectively over model and chart in unison and also rotate in unison. Operations are simplified if one contact and one marker are disposed at the respective axes of rotation of probe head and marker head.

The foregoing and other aspects of our invention will be understood completely in the light of the following detailed description, taken in conjunction with the accompanying drawings in which:

Fig. 1 is a diagram of one form of the apparatus of our invention illustrating the linkage between a rotatable probe head having a pair of contacts for locating equipotential lines on a conductive model and a rotatable marker head equipped with corresponding tracing points for plotting such lines on a chart;

Fig. 2 is a diagram similar to Fig. 1 but illustrating the plotting of flow lines on the chart at right angles to equipotential lines explored in the model;

Fig. 3 is a perspective view of a preferred embodiment of the apparatus of the invention particularly adapted to the investigation of oil field problems;

Fig. 4 is a plan of a conductive model of an oil bearing formation for use with the apparatus of Fig. 3;

Fig. 5 is a partial section through the model of Fig. 4 taken along the line 5-5;

Fig. 6 is an isopachous map of the oil bearing formation of Fig. 4, with flow lines thereon constructed in accordance with the invention;

Fig. 7 is a perspective view of the probe, marker head, and the mechanical linkage of these two elements in the apparatus of Fig. 3;

Fig. 8 is a diagram of the circuit employed in the apparatus of Fig. 3 for manual operation;

Fig. 9 is a diagram of the circuit employed in the circuit of Fig. 3 for automatic operation; and

Fig. 10 is a diagram illustrating a time-scale totaling device incorporated in the apparatus of Fig. 3;

The apparatus of Fig. 1 is arranged for plotting equipotential lines. It comprises an electrolytic model 45 in the form of a basin of insulating material shaped to correspond to the system under-

going investigation, say a wet gas field, and containing a pool of electrolyte. Electrodes 46, 47, 48, 49, corresponding to extraction wells and an electrode 50 corresponding to an injection well, project into the pool from the bottom and receive current from a source 51.

A probe head 52 is supported above the pool and is mounted to rotate on a vertical axis on one end of a horizontal arm or longitudinal slider 52A. The other end carries a marker head 53, likewise rotatable on a vertical axis. A chart or map 54 corresponding to the model in position and orientation is disposed below the marker head.

The probe head carries two probes or contacts 55, 56, for exploring the pool and the marker head has corresponding marker or tracer points 57, 58. Both marker head and probe head are pulleys and are joined by an endless belt 59 so that they are rotated in unison with a line drawn through the contacts always parallel to a line drawn through the tracer points. The probe 55 and the corresponding tracer point 57 are disposed respectively on the axes of the pulleys, so that their companion probe or tracer point (as the case may be) rotates around the member disposed at the axis.

The arm 52A is slidable longitudinally in a holder or lateral slider 60 which rests on a horizontal supporting rail 61 running at right angles to the arm. The holder slides along the rail, so that the probe head may be moved to any portion of the pool with the marker head occupying a corresponding position above the chart. The two contacts are connected to a galvanometer 62, to detect when they are on a line of equipotential.

With the current flowing through the model, the probe head is rotated until the two contacts are at the same potential. The two markers are then depressed to mark corresponding points in the chart. The probe head is then moved until the contact 55 occupies the position formerly occupied by the contact 56 and then the probe is rotated until both contacts are again at the same potential, when the markers are again depressed. In this way a series of points on an equipotential line are determined.

The apparatus of Fig. 2 is identical with that of Fig. 1, except that the line joining the tracing points 57, 58, is at right angles to that joining the contacts on the probe head. Consequently the markers define a flow line at right angles to the equipotential line found by the contacts. When an equipotential line is thus found, the markers are depressed to mark the chart. The marker head is then moved so that one marker point occupies the position formerly occupied by the other. The probe head is then rotated until its contacts are on another equipotential line, when the marker head will have defined a third point on the flow line, the operation being repeated until the flow line is plotted completely.

Referring to Fig. 3 of the drawings, a reduced-scale model 110 of an oil-bearing formation has a conducting pool 112, the geometry of which corresponds to the geometry of the formation as defined by a corrected isopachous map 114. On a typical isopachous map the contour lines represent the thickness of the oil-bearing strata. The oil itself, as well as some connate water, occupies the interstices or pores in the oil sand. In the corrected isopachous map 114, as shown in Fig. 6, the contour lines 116 represent the effective thickness of the actual oil content at various points

in the formation after correction for the volume occupied by sand and water. Oil wells 118A, 118B, 118C, 118D indicated on the isopachous map 114 (see Fig. 6) are represented in the model 110 by fixed electrodes 120, preferably inserted through the bottom of the model for convenience, and projecting into the conducting pool 112. By means of a current control unit 122 electric currents are passed through the fixed electrodes and the conducting pool, the magnitude of the currents bearing a direct relationship to actual or investigated rates of extraction and injection of oil through the oil wells 118A, etc. A multi-electrode exploring probe 123 is provided with two equipotential probing electrodes 124 and 125 and two current flow line probing electrodes 126, 127 which make contact with the conducting pool. The exploring probe 123 is rotatably supported at one end of a supporting device 128. A mapping device 130, rotatably supported at the other end of the supporting device, has tracing points 132, 133 by means of which current flow lines may be indicated on the isopachous map.

The supporting device 128 consists of braces 134 which support a beam 136, a sliding table 138 which is mounted on the beam 136 in such fashion that it may be moved along the length of the beam, and a cross member 140 which in turn is mounted on a sliding table 138 at right angles to the beam and is free to slide lengthwise across the sliding table at right angles to the beam. The exploring probe and the mapping device are also connected together by means of a shaft 142 and worm and pinion gears 144 so that rotational movement of the mapping device about its vertical axis corresponds to rotational movement of the exploring probe about its vertical axis. A phase-sensitive reversible induction motor 146 mounted on the sliding table is geared to the shaft 142 by means of a worm gear 148 to provide means for rotation of the exploring probe and the mapping device under automatic operating conditions. A knob 150 is also provided on the end of the shaft 142 to permit rotation of this shaft when the motor 146 is disengaged and the apparatus is operated manually. A cabinet 152 contains a direction amplifier, a time-scale amplifier, a phase-sensitive induction motor (which operates a calibrated time-scale dial 154), a time-scale totaling device and a revolution counterall of which are employed for automatic operation of the instrument. The time-scale dial, located on the front of the cabinet 152, is calibrated in time units derived from the reciprocal of the voltage drop across the current flow line electrodes 126, 127. The shaft of the dial 154 is an extension of the shaft of a rheostat located inside the cabinet 152. This rheostat forms part of a balancing circuit so designed that for a reasonable range of voltage between the flow line electrodes 126, 127, the movement of the sliding arm of the rheostat required for achieving balance is very nearly proportional to the change in the reciprocal of the voltage differential between electrodes 126, 127. For manual operation a galvanometer 156 is connected across the equipotential probing electrodes 124, 125 to indicate when these electrodes are located at points of equal electrical potential in the conducting pool 112.

As noted above, Figs. 4 and 6 show the reduced-scale model 110 and isopachous map 114, respectively. Both are constructed to the same scale and the contour lines 116 of the map 114 are reproduced sectionally in the model 110, so that the

depth of the conducting pool 112 at any point corresponds to the oil content of the oil-bearing formation at the corresponding location. The oil wells 118 indicated on the isopachous map are represented in the model by the metallic fixed electrodes 120.

Fig. 5 shows the laminated type of construction of the model 110, which is constructed of several layers of plywood. Each layer has had removed from it a sectional area corresponding to a contour line of the map. The individual layers are fastened together and the bottom of the conducting pool 112 is coated with wax 158 so that the sides and the bottom of the pool have a smoothly graduated slope. The electrode 120 is inserted into the pool through a hole drilled in the bottom of the model. A wire lead 160 connected to the lower end of the electrode 120 is run along the bottom of the model for connection of the electrode with the current control unit 122. The pool or basin is filled with an electrically conducting dilute aqueous solution 162 of an electrolyte, which represents the oil content of the oil-bearing formation.

Fig. 7 shows details of the exploring probe 123, the supporting device 128, and the mapping device 130, already referred to in connection with Fig. 3. The exploring probe has a rotatable vertical shaft 164 supported from the cross member 140. An exploring foot 166 attached to the lower end of the shaft 164 comprises an insulation block 168 of a material such as a phenolic condensation product, i. e. machined Bakelite, in which four tungsten rods (which constitute the probing electrodes 124, 125, 126, 127) are mounted. These electrodes are disposed at the four corners of a rhombus, the equipotential electrodes 124, 125 lying on one diagonal and the current flow line electrodes 126, 127 lying on the other diagonal. The axis of the current flow line electrode 126 is the same as the axis of the vertical shaft 164, so that upon rotation of the exploring probe 123 the other three probing electrodes move in circular paths around the electrode 126. Wires 170 attached to the tops of the four probing electrodes are connected respectively to slip rings 172. Brushes 174 contacting the slip rings are provided in order that electrical connections may be made to the probing electrodes without danger of tangling and breaking the connecting wires.

The mapping device 130 has a rotatable vertical shaft 178 supported from the cross member 140. The lower end of the shaft 178 forms the tracing point 132 and is tapered to a slightly blunted or ball-shaped point to allow it to slide over the surface of the map. A cross member 182 is slidably connected at one end to the lower portion of the shaft 178 so as to permit vertical movement thereof. This portion of the shaft 178 is grooved to receive a lug or key 184 on a cross member 182, thereby preventing rotational movement of the cross member 182 with respect to the shaft 178. The other end of the cross member 182 supports the sharp tracing point 133. A spring 186 held in place on the shaft 178 by a collar 188 is provided to maintain the normal position of the tip of the tracing point 133 slightly above the surface of the map. A spring-type push button switch 190 positioned on the shaft 178 is provided to push the sharp tip of the tracing point 133 into the surface of the map during operation of the apparatus and at the same time make an electrical connection at its contact point 191 for operation of a time-scale

totaling device described later in connection with Fig. 10.

The position of the exploring probe 123 in relation to the model 110 and the position of the mapping device 130 in relation to the map 114 are always identical, due to the construction of the supporting device 128. The main support beam 136, which is laterally grooved on both sides, is maintained in a fixed position by means of the braces 134 shown in Fig. 6. The sliding table 138 has a recess shaped to conform to the cross section of the support beam 136 and is free to move laterally with respect thereto. The sliding table 138 also has another recess shaped to conform to the cross section of the cross member 140 and in which that cross member is free to slide laterally at right angles to the support beam 136.

The shaft 142, which connects the exploring probe and mapping device by means of the identical worm and pinion gears 144, is rotatably supported by bearings 192 in brackets 194, which are mounted on the cross member 140. By adjustment of the worm and pinion gears, the relative position and direction of the transfer points 132, 133 is made to coincide with that of the current flow line electrodes 126, 127. Upon rotation of the shaft 142, either manually by means of the knob 150, or automatically by means of the motor 146 shown in Fig. 3, the exploring probe and the mapping device rotate simultaneously, the relative position and direction of the transfer points with respect to the electrodes 126, 127 being identical for any angle of rotation.

Fig. 8 shows the electrical circuit for manual operation of the apparatus. Current is supplied to the fixed electrodes by means of the current control unit. This unit contains a variable autotransformer 196 (for supplying an adjustable source of voltage) an isolation transformer 198, a reversing switch 200, electrode circuits each consisting of a rheostat 202 in series with a precision fixed resistor 204 and a plug-in fixed resistor 206, the value of which is determined by the conditions of the problem. By choosing between sockets 208 and 210, into which one end of the plug-in resistor may be inserted, the phase of current flowing through any fixed electrode may be selected, and the electrode may be made to represent either an injection or extraction well. The other end of the plug-in resistor is inserted in a socket 212. A rectifier type voltmeter 214 is provided for connecting across the precision resistor 204 of any electrode circuit by means of a selector switch, not shown, in order that the voltage drop across the precision fixed resistor 204 may be measured and the magnitude of the current flowing in that circuit determined.

The equipotential probing electrodes 124, 125 are connected to a galvanometer 156, which is of the null indicating type and serves to show whether or not the equipotential electrodes are located at points of equal potential in the conducting pool.

The current flow line electrodes 126, 127 are connected to a time-scale balancing circuit so that the voltage differential across these electrodes is in opposition to a fraction of a standard voltage supplied by an autotransformer 216 and a transformer 218. The input side of the autotransformer 216 is connected to the output side of the autotransformer 196, which regulates the voltage supply in the current control unit. By using the voltage supply for the current control unit as the source of the standard voltage, the current supplied to the fixed electrodes of the

11

model may be adjusted to a convenient level without affecting the relativity of time-scale values obtained as readings on the calibrated time-scale 154.

The time-scale balancing circuit includes a fixed resistance 220 across the balancing circuit and a variable resistance or rheostat 222, in series with the standard voltage. The fraction of standard voltage applied across the resistance 220 in opposition to the voltage across the electrodes 126, 127 is adjusted by means of the rheostat 222, until a galvanometer 224 indicates that the two opposing voltages are in balance. In the balanced position the voltage drop across the resistance 220 is equal to the voltage difference between the electrodes 126, 127. The movement of the sliding arm of the rheostat 222 required to obtain this voltage drop across the resistance 220 is approximately proportional to the change in the reciprocal of the voltage difference between the electrodes 126, 127. The time-scale dial 154 is attached to the axis of the sliding arm of the rheostat 222 by a shaft 226, so that the degree of rotation of the sliding arm, and therefore the amount of resistance placed in the standard voltage circuit by the rheostat 222 is indicated by arbitrary calibrations on the dial. Since the distance between the electrodes 126, 127 is very small as compared to the dimensions of the conducting pool 112, the voltage difference between these electrodes may be considered to be a measure of the potential gradient along a current flow line and this potential gradient may be presumed to be essentially constant at all points between these electrodes. Since potential gradient in the conduction model is analogous to pressure gradient in the corresponding fluid flow system, and since the time required for a unit of fluid to traverse an incremental length of flow line is proportional to the reciprocal of the pressure gradient, the reciprocal of the voltage difference between the electrodes 126, 127 is proportional to the transit time of an element of fluid along the equivalent incremental length of flow line in the fluid flow system. The calibrations on the dial 154 therefore represent transit time for the flow of fluid in the oil-bearing formation in arbitrary time-scale units which are inversely proportional to the total current supplied to the model, and consequently to the total rate of flow of fluid in the formation. The position of the current flow line electrodes 126, 127 with respect to the conducting pool is recorded on the isopachous map of the formation by means of the mapping device and a line connecting the two points indicated on the map by the tracing points 132, 133 represents the portion of the current flow line for which the transit time is determined by the reading obtained on the time-scale dial.

Fig. 9 shows an electrical circuit for fully automatic operation of the instrument of Fig. 3 et seq. The circuits for the current control unit 122 and the time-scale balancing circuit for determining the potential difference between the electrodes 126, 127 are the same as described in connection with Fig. 8 for manual operation.

The exploring probe 123 may be made to automatically seek points of equal potential for the probing electrodes 124, 125 by replacing the galvanometer 156 with a direction amplifier 228, which detects and amplifies any voltage difference existing between these "equipotential" electrodes. Any amplifier capable of handling a 60 cycle signal without introduction of excessive harmonic or phase distortion and having sufficient power output to operate the motor 146 may be used. In

12

the particular case illustrated by Fig. 9, the direction amplifier consists of a single voltage amplification stage resistance coupled to a driver stage which in turn is transformer coupled to a power amplification stage consisting of two 6L6 tubes in push-pull class B operation. The output of the amplifier is applied to the shading pole windings of the phase-sensitive induction motor 146 through an impedance matching transformer contained in the amplifier. In the motor 146 (which is of the reversible shaded pole induction type capable of operation as a 2 phase motor) excitation of the main field windings is obtained by a 110 volt, 60 cycle power supply and excitation of the two sets of shading coils is obtained by means of the output of the direction amplifier 228. When the shading coils are connected in series the direction of rotation of the motor 146 depends on the relationship of the phase of the currents in the main existing field and in the shading coils. If a difference in potential exists between the equipotential probing electrodes, this potential difference is amplified and applied to the shading coils of the servo-motor. As a result the armature of the motor 146 rotates. This causes rotation of the exploring probe 123 in a direction tending to reduce the difference in potential between the equipotential electrodes. When an equipotential state is reached no signal is applied to the amplifier and no excitation is applied to the shading coils, so that no further rotation of the motor takes place. Because of the mechanical linkage between the exploring probe 123 and the mapping device 138, rotation of the latter is obtained simultaneously so that when a state of equal potentials is reached for the equipotential electrodes, the position of the transfer points 132, 133 with respect to the map corresponds to the position of the flow line electrodes 126, 127 with respect to the model.

Operation of the calibrated time-scale dial 154 may also be carried out automatically by replacing the galvanometer 224 of Fig. 8 by a time-scale amplifier 230 and providing a time-scale phase-sensitive induction motor 232 to simultaneously operate the sliding arm of the rheostat 222 and the time-scale dial 154. Any amplifier capable of handling a 60 cycle signal without introduction of excessive harmonic or phase distortion and having sufficient power output to operate the motor 232 may be used. Fundamentally, the construction of the time-scale amplifier is like that of the direction amplifier 228. The output of the amplifier 230 supplies power to the shading pole windings of a time-scale motor 232 through an impedance matching transformer contained in the amplifier.

A shaft 234 connects the sliding arm of the rheostat 222 with the shaft of the motor 232, so that rotation of this motor determines the amount of resistance placed in the balancing circuit by the rheostat. If the fraction of the standard voltage opposing the voltage difference across the electrodes 126, 127 is not exactly equal to this voltage difference, this inequality is applied to the amplifier 230 and the amplified signal in turn operates the motor 232 in a direction tending to reduce the inequality in voltages. Thus the sliding arm of the rheostat 222 is moved to a position which will place in the balancing circuit the exact resistance required for voltage balance.

The calibrated time-scale dial 154 is mounted on the shaft 236 (which in turn is connected to the shaft of the motor 232) so that the dial rotates simultaneously and in accordance with the

sliding arm of the rheostat 222, thereby indicating in arbitrary time units the position of that sliding arm.

The process of manually recording and totaling all of the time-scale readings observed on the calibrated time-scale dial for the numerous individual operations required for establishing each current line charted during the operation of the apparatus may be eliminated by employing a time-scale totaling device 238 and a revolution counter 240. The former is connected by a shaft 242 to the time-scale dial 154 and is controlled by the position thereof.

Details of the time-scale totaling device are shown schematically in Fig. 10. Referring to this figure, a cam 244, mounted on a shaft 242 is driven by the time-scale 232, and is so shaped that the angle through which a feeler arm 246 must advance from its initial zero position to touch the cam 244 is directly proportional to the reading of the time-scale dial 154 throughout the entire scale. The feeler arm is provided at each end with insulated electrical contact pins 248, 250 and is coupled by a friction drive bearing 252 to a shaft 254, which in turn is coupled through a suitable gear train 256 to a shaft 258, and by means of a disengaging-type coupling 259 to a reversible induction motor 260. The shaft 258 of the motor 260 is also coupled through a suitable gear train 262 to a shaft 264 which drives the revolution counter 240 through a ratchet 266 so that the dials of the counter advance on the forward stroke of the feeler arm toward the cam, but are undisturbed on the reverse stroke of the feeler arm to its original or zero position. The dimensions of the cam and the feeler arm are so chosen in conjunction with the gear train 256 and the shaft 264 that an advance of the feeler arm of approximately two degrees corresponds to one revolution of the shaft 264 and hence to one time-scale unit as recorded by the revolution counter.

The power for operation of the time-scale totaling device is obtained from a 110 volt supply by means of a step-down transformer 268 which supplies the power to operate the reversible induction motor 260. A battery 270 is also provided to supply current for actuation of relays 272, 274.

Operation of the totaling device is started by closing the contacts of the push button 190 located on the mapping device 130. This completes the energizing circuit of a coil 276 of the relay 272, thereby closing contacts 278, 280, which are locked into position by a locking key 282.

The power circuit for operation of the motor 260 is completed through the contact 280 of the relay 272 and a contact 284 of the relay 274. Then the feeler arm 246 advances until it touches the cam 244. When contact is made with the cam, the circuit for energizing the coil 286 of the relay 274 is completed, causing contact 284 to open and the contacts 288 and 290 to close. Opening of the contact 284 breaks the power circuit for the forward operation of the motor 260 and the closing of the contact 288 completes the power circuit for reverse operation of the motor 260, thus returning the feeler arm to its original zero position. Closure of the contact 290 insures energization of the coil 286 and serves as a lock to keep the contact 288 in the "make" position.

When the feeler arm returns to its zero position, contact of the pin 250 with a grounded contact 292 momentarily completes the circuit for energization of a release coil 294 of the relay 272, causing the contacts 278, 280 to open. This in

turn deenergizes the coil 286 of the relay 274, opening the contacts 288, 290.

During the return of the feeler arm to its zero position, the counter ratchet 266 slips and the dials of the revolution counter 240 are undisturbed so that the final reading on the dials corresponds to the number of time-scale units indicated by the time-scale dial 154.

The operation of the apparatus is as follows:

The model is constructed to represent an oil-bearing formation on the basis of information obtained from the corrected isopachous map. Such maps are themselves constructed from information derived from geological surveys of the producing area. The outline of the map corresponds to the geometry of the formation and the volume of oil or gas at various locations in the formation is indicated on the map by contour lines 116 for definite increments of volume. In the preparation of the model the horizontal geometry of the conducting pool is made to correspond with that of the map. The vertical geometry is arbitrarily established by making each layer of plywood correspond to one or more contour lines and the resulting reduction in scale as compared to the actual formation is greater in the horizontal plane than in the vertical plane. The completed model is placed in position under the exploring probe and the leads from the fixed electrodes representing wells are connected to the current control unit. The isopachous map is correspondingly placed in position under the mapping device. The conducting pool 112 is filled with a dilute aqueous solution of an electrolyte such as copper sulfate or other ionizable salt. The exact concentration of salt in the solution is not critical but the conductivity of the solution should be low in order that the potential drop between the current flow line electrodes 125, 127 will be of an easily measurable magnitude at low current densities.

The electric currents passing through each electrode are adjusted in direct relationship to the rates of extraction or injection of fluid in the corresponding oil wells. Adjustment of the individual currents passing through each electrode is obtained by means of the variable resistors 202 and the fixed plug-in resistors 206. By selecting between the terminals 208, 210 for the fixed plug-in resistors 206 it is possible to select the desired direction of current flow for any fixed electrode and thereby simulate either an injection well or an extraction well.

The current flow line electrode 126 of the exploring probe 123 is placed at the desired starting point, ordinarily adjacent to one of the fixed electrodes 120, by moving the sliding members of the supporting device.

For manual operation of the instrument, the exploring probe is rotated by turning the knob 150 until the galvanometer 156 connected to the exploring electrodes 124, 125 (i. e. the equipotential electrodes) registers zero. The rheostat 222 is then adjusted by means of the knob of the time-scale dial 154 until the galvanometer 156 registers zero. The inverse of the difference in potential between the flow line electrodes 126, 127 is then read as arbitrary time units from calibrations of the time-scale dial 154. The sliding members of the supporting device 128 are then moved so that the tracing point 132 occupies with the former position of the other tracing point 133, and the process is repeated until a current line is traced out on the isopachous map as far as desired. For each operation the read-

ing of the calibrated time-scale dial 154 is recorded and the sum of the individual values corresponds to the total transit time of an element of fluid along a corresponding path in the formation. A permanent record of each current line is obtained by drawing a curve through the individual points mapped out by the tracing points 132, 133.

Fig. 6 is an isopachous map of a wet gas field having an injection well 118A and three extraction wells 118B, 118C, 118D. On it have been plotted a number of flow lines obtained for an assumed dry gas input rate at the injection well and assumed extraction rates of wet gas at the other wells. Each flow line is obtained by placing the flow line electrode 128 of the exploring probe close to the electrode 120 corresponding to the injection well, the tracing point 132 occupying a corresponding position on the map. The apparatus is then permitted to seek the equipotential line, with the result that the tracing point 133 rotates about the other tracing point to locate a point on the flow line, i. e. a line normal to the equipotential line. The button 130 is then pushed down so that the tracing point 133 marks the chart. Then the probe and the marking device are moved so that the tracing point 132 is on the mark made by the point 132, and the operation is repeated. Each time it is repeated a new point on the flow line is obtained.

As each flow line is traced, the corresponding transit time is noted by the time-scale totalizer, and the accumulated transit times is noted at each point along the flow line. After the series of flow lines are plotted, with transit times noted at points along each line, points of equal transit time on the several lines are joined by cross lines (indicated as "Dry Gas Invasion Fronts" on Fig. 6). Each such invasion front shows the extent of dry gas penetration into the field after a given time interval for the assumed extraction and injection rates. It will be noted that the lower of the two invasion fronts plotted has reached the well 118C, indicating "break through." This means that the extraction rate assumed for the well 118C is too high in relation to those assumed for wells 118B and 118D, for the rates should be such that break through is accomplished simultaneously for each well. To assure optimum production from the field, flow lines and invasion fronts should be plotted again with new assumptions, until "break through" occurs simultaneously at all three extraction wells. Moreover, the results plotted on Fig. 6 show that a fourth extraction well should be placed in the field at or about position 400 in order to assure proper recovery from this portion of the field.

As already mentioned, various operations can be carried out automatically. For example, the rotation of the exploring probe 128 can be achieved automatically by means of the motor 148 operated by the direction amplifier 228. The balancing of the rheostat 222 can be performed automatically by means of the motor 232 operated by the time-scale amplifier 230. By means of the time-scale totaling device 238 and the revolution counter 240, time-scale units for any specified interval along a current flow line may be computed automatically as the current flow line is traced.

In automatic operation the exploring probe will rotate to obtain a position such that no potential difference exists between the equipotential

electrodes 124, 125. As long as any difference in potential exists between these electrodes, it is applied to the direction amplifier 228 and the amplified voltage is applied to the shading coils of the motor 148 to cause rotation of the motor in a direction such that the exploring probe is turned to a position where no difference in potential occurs between the equipotential probes. During the time the exploring foot or probe is thus oriented, the time-scale balancing circuit is also seeking a balance through the adjustment of the rheostat 222, and the rheostat will come to rest shortly after the direction system has reached a balance. This is achieved through the potential balancing circuit and the time-scale amplifier 230 and the motor 232. As long as the fraction of the standard voltage supplied from the transformer 218 in opposition to the potential difference between the flow line electrodes 126, 127 does not exactly balance this potential difference, the difference in voltage is applied to the time-scale amplifier 230, where it is amplified, the amplified voltage being applied to the shading coils of the motor 232. This results in the rotation of that motor in a direction to rotate the sliding arm of the rheostat 222 to a position where the applied fraction of standard voltage exactly balances the potential difference between the flow line electrodes 126, 127. With both direction and time systems at balance the instrument indicates both the direction of the current flow line by the angular position of the exploring foot and the equivalent transit time across that section of flow line by the reading of the calibrated time-scale dial 154. This information may be recorded by pressing the push button 130 on the mapping device 138. This simultaneously depresses the tracing point 133 to make a punch mark on the isopachous map and also closes the electrical contacts 191, which cause the time-scale totaling device 238 to register on the counter 240 the time units indicated by the time-scale 154. The relation of the arbitrary time-scale units indicated by the apparatus and the time of flow of fluid through the oil-bearing formation is a function of the relationship of the current applied to the fixed electrodes 120 with respect to the flow rates of fluid in and out of the formation through the oil wells 118 and the total volume of fluid in the formation.

Various designs are possible for the potential balancing circuit and the direction of time-scale amplifiers as well as in the probe and the other elements of the apparatus. Likewise, the specific design of the time-scale totaling device is not a limitation of the invention and any equivalent mechanism may be employed. Because of the wide variations in potential gradient which can occur over the surface of the conducting pool it is sometimes desirable to provide two or even more time unit scales to achieve greater accuracy in determining transit time values.

In the operation of the apparatus of Figs. 3 to 10 inclusive, as described above, flow lines and flow rates are obtained directly, and the equipotential lines are not recorded. This practice is followed because, in oil field studies the equipotential lines usually are not relevant. However, in other engineering problems the shape and location of equipotential lines may be important, and it is a simple matter to record them. Thus as shown in Fig. 8, the leads extending from the equipotential probes 124, 125 to the galvanometer

156 may be interchanged with the leads from the flow line probes 126, 127 which extend to the other galvanometer 224 by means of a quadruple pole double throw switch 365. The tracing points 132, 133 will then define an equipotential line instead of a flow line, as described in connection with Fig. 1.

It may be desirable to know what the potential is along any particular equipotential line, and this can be determined, as illustrated in Fig. 8, 10 by employing a galvanometer 366 connected between the slider of a potentiometer 367 and one of the exploring electrodes employed to find the equipotential line, say the electrode 126, the end points of the potentiometer being connected between an "injection" electrode and an "extraction" electrode.

We claim:

1. In a device for determining the condition of a system operating at least approximately in accordance with Laplace's equation, the combination which comprises an electrically conductive body the shape of which is analogous to the system undergoing investigation, means for impressing across the body an electrical potential analogous to the force impressed upon the system, chart supporting means, a probe member having at least three electrical contacts spaced from and out of line with each other and adapted to contact the body, means for measuring the potential between one set of two of the contacts, means for measuring the potential between another set of two of the contacts which define a line transverse to that defined by the first set, a marker member having a plurality of markers spaced from each other and disposed adjacent the chart, means for moving the probe member and the marker member in unison to corresponding positions respectively in the body and the chart, means for rotating the contacts on the probe member and the markers on the marker member in unison through corresponding angles, and means for contacting the markers with the chart.

2. Apparatus according to claim 1 provided with a pair of markers on the marker member so disposed that a line drawn between them is oriented with respect to chart in the same way that a pair of contacts on the probe member are oriented with respect to the body.

3. Apparatus according to claim 1 provided with a pair of markers on the marker member which are oriented on the chart at right angles to the orientation of a pair of contacts on the probe member with respect to the body.

4. In a device for determining the condition of a force system operating at least approximately in accordance with Laplace's equation and having an electrically conductive body the shape of which is analogous to the system and means for impressing across the body an electrical potential analogous to the force impressed upon the system, the combination which comprises chart supporting means, a rotatable probe member having at least three electrical contacts spaced from and out of line with each other and arranged to contact the body, one of the contacts being disposed on the axis of rotation of the probe member, means for measuring the potential between a first set of two of the contacts, means for measuring the potential between another set of two of the contacts which define a line transverse to that defined by the first set, a rotatable marker member having a plurality of markers

spaced from each other and disposed adjacent the chart with one of the markers disposed on the axis of rotation of the marker member, means for contacting the markers with the chart, means for moving the probe member and the marker member in unison to corresponding positions respectively on the body and on the chart and means for rotating the probe member and marker member in unison through corresponding angles.

5. In a device for determining the condition of a system operating at least approximately in accordance with Laplace's equation and including an electrically conductive body analogous in shape to the system and means for impressing across the body electrical potential analogous to force impressed upon the system, the combination which comprises a chart supporting means, a rotatable probe member having at least three contacts spaced from each other and disposed to contact the body in a pattern which defines a right angle, means for measuring the potential between a first set of two of the contacts, means for measuring the potential between another set of two of the contacts which define a line at right angles to that defined by the first set, a rotatable marker member having two markers spaced from each other and disposed adjacent the chart, means for moving the probe member and the marker member in unison to corresponding positions respectively on the body and on the chart, means for rotating the probe member and the marker member in unison through corresponding angles and means for pressing the markers against the chart.

6. In apparatus for determining dynamic characteristics of a steady state system upon which forces operate, the combination which comprises an electrical model of the system including an electrical conductor analogous in shape to the system and means for impressing thereon electrical currents analogous to forces acting upon the system, a chart of the system, a probe member having two electrodes rotatable about a common axis to positions of equipotential on the conductor, means for measuring the potentials between the two electrodes, an auxiliary electrode mounted on the probe out of line with the first two electrodes but rotatable about the same axis, means connected to the auxiliary electrode for measuring potential gradient in said conductor along a current flow line transverse to the line joining the first two electrodes and passing through the auxiliary electrode, a marker member having at least two markers spaced from each other contactable with the chart and rotatable about a common axis and means for moving and rotating the marker member and the probe member simultaneously and in synchronism with each other so that the markers locate on the chart a line corresponding to that on the conductor along which the potential gradient is measured.

7. In apparatus for determining dynamic characteristics of a steady state system upon which forces operate, the combination which comprises an electrical model of the system including an electrical conductor analogous in shape to the system and means for impressing thereon electrical currents analogous to forces acting upon the system, a chart of the system, a probe member having two electrodes rotatable about a common axis to a position of equipotential on the conductor, means for measuring the potentials between the two electrodes, means connected to

the potential measuring means for automatically rotating the electrodes to the position of equipotential, an auxiliary electrode mounted on the probe out of line with the first two electrodes but rotatable about the same axis, means connected to the auxiliary electrode for measuring potential gradient in said conductor along a current flow line normal to the line joining the first two electrodes and passing through the auxiliary electrode, a marker member having at least two markers spaced from each other contactable with the chart and rotatable on a common axis and means for moving and rotating the marker member and the probe member simultaneously and in synchronism with each other so that the markers locate on the chart a line corresponding to that on the conductor along which the potential gradient is measured.

8. In apparatus for determining dynamic characteristics of a steady state system upon which forces operate, the combination which comprises an electrical model of the system including an electrical conductor analogous in shape to the system and means for impressing thereon electrical currents analogous to forces acting upon the system, a chart of the system, a probe member having two electrodes rotatable about a common axis to positions of equipotential on the conductor, means for measuring the potentials between the two electrodes, an auxiliary electrode mounted on the head out of line with the first two electrodes but rotatable about the same axis, means connected to the electrode for measuring the reciprocal of potential gradient in the conductor along a current flow line passing through the auxiliary electrode and transverse to a line joining the first two electrodes, a marker member having at least two markers spaced from each other contactable with the chart and rotatable about a common axis and means for moving and rotating the marker member and the probe member simultaneously and in synchronism with each other so that the markers locate on the chart a line corresponding to the current flow line on the conductor along which the potential gradient is measured.

9. In apparatus for determining dynamic characteristics of a steady state system upon which forces operate, the combination which comprises an electrical model of the system including an electrical conductor analogous in shape to the system and means for impressing thereon electrical currents analogous to forces acting upon the system, a chart of the system, a probe member having two electrodes rotatable about a common axis to positions of equipotential on the conductor, means for measuring the potentials between the two electrodes, means mounted on the head and rotatable about the same axis as the first two electrodes for locating a line in the conductor transverse to that passing between the first two electrodes, means for measuring the reciprocal of potential gradient along the line located by said means, a marker member having at least two markers spaced from each other contactable with the chart and rotatable about a common axis, means for moving and rotating the marker member and the probe member simultaneously and in synchronism with each other so that the markers locate on the chart a line corresponding to that on the conductor along which the reciprocal of potential gradient is measured, and means for adding a series of said reciprocals measured with the probe at different points in the conductor.

10. In apparatus for determining dynamic

characteristics of a steady state system upon which forces operate, the combination which comprises an electrical model of the system including an electrical conductor analogous in shape to the system and means for impressing thereon electrical potentials analogous to forces acting upon the system, a chart of the system, a probe member having two electrodes rotatable about a common axis to positions of equipotential on the conductor, means for measuring the potentials between the two electrodes, electrode means mounted on the probe at right angles to the two electrodes and rotatable therewith about the same axis, means connected to the electrode means for measuring the potential gradient in the conductor along a current flow line at right angles to that between the two conductors, a marker member having at least two markers spaced from each other contactable with the chart and rotatable about a common axis and means for moving and rotating the marker member and the probe member simultaneously and in synchronism with each other so that the markers locate on the chart a line corresponding to that on the conductor along which the potential gradient is determined.

11. In apparatus for determining the progress of the interface between a fluid in place in a porous body and an invading fluid, the combination which comprises a conductor analogous in shape to the body, means for impressing across the conductor current analogous to the rate of invasion, a probe having a pair of spaced electrodes rotatable about a common axis in contact with the conductor, means for measuring the potential between the pair of electrodes, means mounted on the probe for locating a line in the conductor at right angles to a line joining the pair of electrodes and including an auxiliary electrode rotatable about the same axis as the pair of electrodes, means for measuring the potential gradient along the line thus located, and means linked to the probe for plotting on a chart of the body the line along which the potential gradient is determined.

12. In apparatus for determining flow of petroleum in a petroleum-bearing formation comprising a model of the formation in which the petroleum content of the formation is represented by a pool of electrolyte and in which production and injection wells are represented by electrodes positioned in the electrolyte, the combination which comprises an exploring probe having at least three electrodes in fixed geometrical relation to each other and arranged to contact the pool, means for moving the probe with respect to the pool, means for rotating the first two of the electrodes of the probe on a common axis to points of equal electrical potential in the pool, means including the third electrode of the probe for measuring potential gradient in the pool along a current flow line at right angles to a line drawn through lines of equal electrical potential located by the first two of the electrodes, a mapping device, means for moving the mapping device and the probe simultaneously to corresponding positions, coupling means for obtaining simultaneous rotation of the probe and the mapping device, means for measuring the reciprocal of the potential gradient and means for totaling the reciprocal obtained at successive positions of said probe along the current flow lines.

13. In a device for determining flow characteristics of petroleum in a petroleum-producing formation comprising a reduced scale model in

21

which the petroleum content of the formation is represented by a pool of electrolyte and in which production and injection wells are represented by electrodes located in said pool, the combination which comprises an exploring probe having two equipotential electrodes and two current flow electrodes so disposed that lines drawn through the two kinds of electrodes cross at right angles, means for moving the probe over the pool to bring the electrodes in contact therewith, a mapping device for graphically recording on a map the position of said current flow electrodes in the pool, thereby determining a current flow line, means for moving the probe and the mapping device simultaneously to corresponding positions respectively on the pool and the map, coupling means for rotating the probe and the mapping device simultaneously and for bringing the equipotential electrodes to a position of balanced potential in the pool, means for measuring the reciprocal of the potential difference between the points of contact of the current flow line electrodes in the pool along the current flow lines, and means for totaling the reciprocals obtained at successive positions of said probe along the current flow line.

14. In a device for determining dynamic characteristics of a steady state system, the combination which comprises an electrically conductive body the shape of which is analogous to the system undergoing investigation, means for impressing across the body an electrical voltage analogous to the force impressed upon the system, a probe member having two electrodes movable to positions of equipotential on the conductor, means for measuring the potential between the two electrodes, at least one auxiliary electrode mounted on the probe in fixed spacial relationship to the other two electrodes, means connected to the auxiliary electrode for measuring potential gradient in the conductor along a line passing through the auxiliary electrode and transverse to that connecting the other two electrodes.

15. In a device for determining dynamic characteristics of a steady state system, the combination which comprises an electrically conductive body the shape of which is analogous to the sys-

22

tem undergoing investigation, means for impressing across the body an electrical voltage analogous to the force impressed upon the system, a probe member having two electrodes movable to positions of equipotential on the conductor, means including a third electrode mounted on the probe for measuring the reciprocal of the potential gradient in the conductor along a line transverse to that between the first two electrodes, and means for adding a series of said reciprocals measured with the probe at successive points in the conductor along the line.

16. In a device for determining dynamic characteristics of a steady state system, the combination which comprises an electrically conductive body the shape of which is analogous to the system undergoing investigation, means for impressing across the body an electrical voltage analogous to the force impressed upon the system, a probe member having two first electrodes movable to positions of equipotential on the conductor, and multiple electrode means mounted on the probe at right angles to a line joining the two first electrodes and movable therewith for measuring the potential gradient in the conductor along a line at right angles to that between the two first electrodes.
